[57] CLAIM

The ornamental design for a double dresser, as shown and described.

DESCRIPTION

FIG. 1 is a top plan view of a double dresser showing my new design;

FIG. 2 is a front elevational view thereof;

FIG. 3 is a right side elevation view of a double dresser as seen when in use, the left side being a mirror image thereof; and,

FIG. 4 is a right front top perspective view of a double dresser as seen when in use.

The rear forms no part of the claimed design.
